UNITED STATES PATENT OFFICE.

WILLIAM H. PERRY, OF CONCORD, NEW HAMPSHIRE.

DESIGN FOR A MONUMENT.

SPECIFICATION forming part of Design No. 22,593, dated July 4, 1893.

Application filed June 2, 1893. Serial No. 476,397. Term of patent 7 years.

To all whom it may concern:

Be it known that I, WILLIAM H. PERRY, a citizen of the United States, residing at Concord, in the county of Merrimac and State of New Hampshire, have invented and produced a new and original Design for Monuments, of which the following is a specification, reference being had to the accompanying drawing.

The leading features of my design consist in the particular shape and configuration of the base, pedestal, and shaft, the various ornamentalations and the character of the surfaces of the different parts, all of which will be fully set forth and described in the following specification and claim and clearly illustrated in the accompanying drawing forming a part thereof.

Reference is had to the drawing by figures and letters.

The base 1, is oblong and has four vertical sides and terminates in an obtuse frustum of a pyramid as seen at 2. Resting upon the frustum 2, is the pedestal 3 having four vertical sides and terminating in an obtuse frustum 4, of a pyramid, upon which rests the shaft 5 which is also oblong and has four vertical sides terminating at their tops in castellations or battlements 6, the tops 7, of which extend inward and meet the acute frustum 8, of a pyramid, which forms the top of the shaft.

Further ornamentation of my design consists in the tablets 9, 10, and 11;—in the corners of the shaft, which are provided for a portion of their height with sort of a quirk bead 12; and in ornamentation of the various parts by surfaces of a different character, comprising rock-work, hammered work, and polished work, designated respectively by the letters A, B, C. The tablet 9, is raised and highly polished, and may be placed on one or more sides of the frustum 4. The tablet 10, is depressed in one or both the long sides of the shaft 5, the depression being rectangular with an ornamentation denoted by a border line 13, having the configuration shown. The tablet 11, is of rock-work and covers the top of the frustum 8, within an ordinary draft line. The shaft may be further ornamented if desired by a quirk bead 14 located between the tablet 10 and the castellations 6.

What I claim as my invention is—

The design for a monument substantially as herein shown and described.

In testimony whereof I affix my signature in presence of two witnesses.

WILLIAM H. PERRY.
